US00D883014S

(12) **United States Design Patent** (10) **Patent No.:** **US D883,014 S**
(45) **Date of Patent:** **** May 5, 2020**

(54) **FOOD PREPARATION DEVICE**

(71) Applicant: **SHARKNINJA OPERATING LLC**,
Needham, MA (US)

(72) Inventors: **Nicholas Varjabedian**, Middleboro,
MA (US); **Benjamin Lenart**, Malden,
MA (US)

(73) Assignee: **SHARKNINJA OPERATING LLC**,
Needham, MA (US)

(**) Term: **15 Years**

(21) Appl. No.: **29/659,571**

(22) Filed: **Aug. 9, 2018**

(51) LOC (12) Cl. **07-02**

(52) U.S. Cl.

USPC **D7/354; D7/358**

(57) **CLAIM**

The ornamental design for a food preparation device, as shown and described.

DESCRIPTION

FIG. 1 is a perspective view of a food preparation device, showing our new design;

FIG. 2 is a front view of the embodiment shown in FIG. 1;

FIG. 3 is a rear view of the embodiment shown in FIG. 1;

FIG. 4 is side view of the embodiment shown in FIG. 1;

FIG. 5 is another side view of the embodiment shown in FIG. 1;

FIG. 6 is a top view of the embodiment shown in FIG. 1;

FIG. 7 is a bottom view of the embodiment shown in FIG. 1;

FIG. 8 is another perspective view of the embodiment shown in FIG. 1, as shown in an alternate configuration; and,

FIG. 9 is still another perspective view of the embodiment shown in FIG. 1, as shown in an alternate configuration.

The broken lines in the figures are for environmental purposes only and form no part of the claimed design.

1 Claim, 9 Drawing Sheets
